UNITED STATES PATENT OFFICE.

ERNEST O. LINTON, OF HAMMOND, INDIANA, ASSIGNOR TO LINTON GASOLINE PROCESS COMPANY, OF CHICAGO, ILLINOIS, A CORPORATION OF DELAWARE.

APPARATUS FOR CRACKING OIL.

Application filed October 17, 1922. Serial No. 595,144.

My invention relates to the continuous cracking of hydrocarbon oils, and particularly heavy oils, having an asphaltic base, such as Mexican panuco oil and asphaltic 5 and semi-asphaltic fluxes.

The apparatus comprises a vaporizing chamber within which the oil is caused to flow in a thin stream over extended heated surfaces whereby the vaporizable constituents are freely liberated. In combination with this heated chamber I use a second heating chamber or retort into which the heated vapor mixtures from the vaporizing chamber are directly introduced. In this 10 retort the vapors are permitted to expand, and caused to flow over highly heated surfaces, this further heating being conducted in the absence of super-atmospheric pressure. The apparatus preferably also 15 comprises a second vaporizing chamber similar in construction to that above mentioned, for dehydrating the crude oil before it is vaporized. My invention further relates to 20 features of construction of the vaporizing chambers and the retort, to their special construction and arrangement, to the means for applying heat, and to other features of construction which will appear from the accompanying drawing, specification and 25 claims.

In the accompanying drawing Fig. 1 is a central longitudinal section on the plane B—B of Fig. 3;

Fig. 2 is a similar section taken on the plane A—A of Fig. 3 at right angles to the section on which Fig. 1 is taken.

Fig. 3 is a plan view of the apparatus.

Fig. 4 is a sectional elevation of a condenser unit and its connections.

Fig. 5 is an enlarged view of the expansion nozzle.

Referring to Figs. 1 and 2, A and B are like heating chambers which may be used either for dehydrating or vaporizing purposes.

Each one of these chambers comprises a generally cylindrical horizontal shell 1 and a dome 2, from which vapor pipes 3—3 lead through a connection 4, preferably formed as an expanding nozzle, into 50 the retort C.

Oil feed pipes 5 extend into each of the heating chambers near the top, and are perforated. From these perforations the oil is delivered on to inclined plates 6—6, having 55 their upper edges beneath the oil feed pipes,

and their lower edges near the wall of the shell. The oil flows from the edges of these plates 6—6 on to inclined walls 7—7, spaced several inches from the actual outer wall of the chamber. Additional deflecting plates 60 8—8 may be provided to take care of the overflow from the plates 6—6. These plates are supported within the shell in any suitable manner by metallic connections so that they are heated both by conduction and radiation from the walls of the shell. The unvaporized portion of the oil flows down the walls 7—7 into a drain 9 at the bottom through which it is withdrawn from the heating chamber. No oil is allowed to accumulate in these vaporizing chambers, so that the vapors are freely liberated from a shallow stream or film of oil into a large open space.

When the chamber A is used for dehydrating, the dehydrated oil flows through pipe 10, pump 11 to the oil feed pipes 5—5 of the vaporizing chamber B, the exit pipe 12 from chamber B then carrying off the asphalt or other heavy residue. By providing similar pipe connections chamber B may be used for dehydration and chamber A for vaporizing, or both may be used for vaporizing.

The vapor cracking retort C is mounted 85 above the horizontal chambers A and B, and is preferably of the general shape shown comprising an outer shell 13 and an inner filling chamber 14, spaced from but supported by the shell. The filler chamber 90 may be left vacant or may be filled with some refractory heat retaining material, such as ganister. The mixed vapors in passing through this large but shallow space are heated throughout their mass by contact with extended hot surfaces. While I have shown one particular form of retort, other arrangements may obviously be used for the same purpose.

The vapors pass from the main body of 100 the vaporizing chamber C to the dome 15 through a contracted orifice 16, and thence through exit pipes 17 to a condensing system, diagrammatically shown in Fig. 3. Preferably the condensers are formed as 105 deep, narrow boxes 18 immersed in a cooling liquid, as shown in Fig. 4. The upper ends of these condenser boxes are connected to headers 19 connected to a suction pump 20 by which any non-condensed gases are 110

delivered to a secondary condensing system (not shown), this pump also serving to prevent any substantial super-atmospheric pressure in the system.

5 The vaporizing retort C is heated by means of gas or oil burners 21—21, arranged as shown in Fig. 3. From the burner chambers the products of combustion pass into several layers of checkerwork 22, and 10 thence around the outer shell of the retort, the hot gases being preferably kept in contact with the outer walls of the retort by a supplemental shell 23.

This vapor cracking retort is mounted in 15 a housing 24 made of brick or other suitable refractory material. From the housing 24 the products of combustion pass into flues 25 connected to pipe 26 leading to the stack 27, this passage being controlled by a butterfly valve 28. From the pipe 26 depends a pipe 29 from which branch pipes 30 deliver the hot products of combustion into the spaces between partitions 60 and the 20 roof of the housings within which are mounted the vaporizing chambers A and B. The products of combustion pass into one 25 end of this housing over the top and along the length of the vaporizing chambers and then down through a passage 31 in the other 30 end of these chambers, and thence back over the lower portions of these chambers into the exit flue 32 leading to the stack. Supplemental burner chambers 33 are provided on each side of the vaporizing chambers, the 35 products of combustion therefrom passing upward through the passage 34 and through openings 35 in the wall 36 into contact with the vaporizing chambers.

The otherwise waste products of combustion 40 from burners 21 can thus be used to furnish heat to the vaporizers A and B, the supplemental burners being used when necessary. The vapor pipes 3 are provided with valves 37 and to each of the domes 2—2, is 45 connected an additional exit pipe 38 which is connected to a condenser. By making appropriate connections, either one of these chambers may be used as a dehydrator, or as an oil vaporizing chamber. When used 50 as a dehydrator the water vapors pass off and are led by the pipe 38 to condenser, the corresponding pipe 3 being closed.

The mode of operation is as follows:

Assuming that the chamber A is being 55 used as a dehydrator to remove water from the crude oil, the oil which may be preferably heated, is delivered through the perforated pipes 5—5 from which it flows down over the plates 6—6 and 7—7, which by 60 reason of their location in and connection to the hot shell are themselves heated to the requisite temperature. This temperature, which should be about 400° F., can be ascertained by means of a pyrometer located 65 in the space between the plates 7—7 and the

shell of the chamber. By the passage of the oil in a continuously flowing film over these extended surfaces, within the heated chamber, the water is evaporated from the oil, the vapors passing upward to the dome 2, and 70 thence to the exit pipe 38. This apparatus has been found to be successful in entirely freeing even heavy asphaltic oils from water, this freedom from water being highly important as the presence of water in the 75 oil which is to be vaporized has highly detrimental effects because the liberated vapor are not free from globules of oil which are carried over into the vapor cracking chamber and tend to produce fixed gas, and to 80 facilitate the deposition of carbon.

The water-free oil passes out through the pipe 10 from which it is delivered by the pump 11 to the oil feed pipes 5—5 of the vaporizing chamber B. From the perforated pipes the oil again flows in a continuous film over the extended surfaces of the plates 6—6 and 8—8 of this chamber, and thence over the downwardly inclined walls 7. In this chamber a higher temperature is maintained. The temperature in dome 2 should be from 800° to 850° F., and the temperature in the space between the plates 7 and the wall of the shell about 850° F. This dead air space prevents the 90 plates 7—7 from being subjected to the actual heat of the flame or hot gases impinging against the outer surface of the shell itself, thereby preventing any carbonization 95 of the oil flowing over these plates. 100

In this chamber B the oil is not only vaporized but a partial cracking occurs. The mixed mass of vapors containing all the desirable volatilizable constituents of the oil, i. e. those having boiling points above that of the asphaltic base or heavy residuum, is then delivered through the pipe 3 and nozzle 4 into the vapor cracking chamber C. A slight excess of pressure may exist in the pipe 3, but as the hot mixed vapors pass through the opening of the nozzle 4, which is of less diameter than the pipe 3, the gases are expanded into the large space within the vapor cracking chamber C, and are compelled to pass between the walls of the filler 105 14 and the wall 13 of the chamber, the entire sheet or film of vapors being heated throughout its mass to the requisite temperature, which should be about 1050° to 1100° F., as shown by suitably located pyrometers. From the body portion of the vapor cracking chamber the vapors pass 110 through the orifice 16 to the dome 15 and thence to the condenser. The temperature of the vapors as they leave the dome should 115 be from 1050° to 1100° F. 120

The temperatures specified are those which have been found by experience to be best to obtain the desired results, but obviously 125 they may be varied to some extent as the 130

character of material operated upon and other conditions of operation vary.

By means of the suction pump 20 a rapid flow of vapors through the system is maintained, as no super-atmospheric pressure is necessary or desirable.

I have found in practice that it is desirable to separate the vaporizing chamber from the cracking retort as it is thereby possible to accurately control the conditions in each chamber, while at the same time providing sufficient heating surface to adequately vaporize a large quantity of oil in continuous flow, and to thoroughly crack these vapors under definitely controlled conditions as to temperature and time of treatment.

My apparatus therefore provides a controlled means for producing the temperatures necessary to effect the vaporization of the oil and the cracking of the vapors, and also provides means for controlling the rates of flow (time of treatment) both of liquid and vapors, so that all the desirable vaporizable ingredients are vaporized and effectively cracked, to produce lighter hydrocarbons.

The entire apparatus has therefore a large capacity, is relatively inexpensive, and exceedingly efficient in operation.

As a general indication of the result obtained by the application of my method to a heavy asphaltic base oil, the condensate obtained from the condenser constitutes about 60% of the original oil, and upon fractional distillation yielded about 65% of gasoline, the remainder being added to the original oil and re-run.

I claim:

1. An oil cracking apparatus comprising 40 a vaporizing chamber and means for heating the same, said chamber having therein extended inclined plates, means for delivering oil to and above said plates, and an exit pipe at its bottom; a vapor cracking retort 45 constructed and arranged to provide for the vapors a shallow passage, having heated walls, means for heating said retort, and a conduit of less diameter than the retort connecting the vaporizing chamber and the 50 lower portion of said retort.

2. An apparatus as claimed in claim 1 in which the vapor cracking retort is connected to the conduit through an expansion nozzle.

3. An apparatus as claimed in claim 1 in 55 which the lower portion of the vapor cracking retort is conical and has a similarly shaped filler spaced therefrom to form a shallow vapor passage.

4. A vaporizing chamber comprising a 60 cylindrical shell, longitudinally extending inclined plates located in the upper portion of the shell and having their lower edges in proximity to the wall of the shell, perforated pipes for delivering oil located above said 65 plates, said shell having means for withdrawing residuum from its bottom and vapor from its top, and means for heating the same.

5. A vaporizing chamber as claimed in 70 claim 4 in which the shell is provided below the plates with inclined plates having their upper and lower edges only in contact with the shell.

In testimony whereof, I affix my signature.

ERNEST O. LINTON.
